CLAIM

The ornamental design for a toaster, as shown and described.

DESCRIPTION

FIG. 1 is a top and side perspective view of a toaster showing my new design, with two of the four swinging racks being shown in the open position;

FIG. 2 is a top plan view thereof with all four racks being shown in the open position;

FIG. 3 is a bottom plan view thereof with all four racks being shown in a closed position; and

FIG. 4 is a side elevational view thereof on an enlarged scale with the racks being shown in the open position, it is understood that the four sides of the toaster are identical except for the top ornament.

fig. 4
